UNITED STATES PATENT OFFICE.

CHARLES C. BAUDER, OF BURNSIDE, ILLINOIS, ASSIGNOR TO HIMSELF AND
GEORGE E. BAUDER, OF VALLEY CITY, DAKOTA TERRITORY.

TRACE-BUCKLE.

SPECIFICATION forming part of Letters Patent No. 298,934, dated May 20, 1884.

Application filed December 10, 1883. (No model.)

To all whom it may concern:

Be it known that I, CHARLES C. BAUDER, of Burnside, in the county of Hancock and State of Illinois, have invented a new and Improved 5 Trace-Buckle, of which the following is a full, clear, and exact description.

Reference is to be had to the accompanying drawings, forming part of this specification, in which similar letters of reference indicate corresponding parts in all the figures.

Figure 1 is a sectional plan view of my new and improved trace-buckle as it appears when in use, and Fig. 2 is a side elevation of the same. Figs. 3 and 4 are side and plan views, 15 respectively, of the main part of the buckle; and Figs. 5 and 6 are sectional and plan views, respectively, of the grip-loop.

The invention will first be described in connection with the drawings, and then pointed 20 out in the claims.

Referring to the drawings, A represents the rear and main part of the buckle, which holds the forward end of the tug B by means of the tongues $a' c'$, passing through suitable holes 25 made through the tug, and C represents the forward part (which I term the "grip-loop") of the buckle attached to the rear end of the hame-tug D. The main part A of the buckle is made in skeleton form and of considerable 30 length, with the end cross-bars, $a b$, and central cross-bar, c , and it is curved outward at its rear end to permit the tug B to pass under the cross-bar a and over the cross-bars $b c$, as shown in Fig. 1. The cross-bars $a b$ are formed 35 or provided, respectively, with the above-named tongues $a' c'$, which hold the tug B, and these tongues project in opposite directions—that is, the tongue a' projects inward, while the tongue c' projects outward—so that 40 these tongues are adapted to enter the holes made in the tug B from opposite sides of the tug. The grip-loop C is attached to the hame-tug D by means of the bolt or screw f , and the side bars, $e e$, of the loop are bent to pass 45 up through the main part A between the cross-

bars b and c thereof, and allow the tug B to pass through it under the outer cross-bar, f' . The outer edges of the side plates, $e e$, of the grip-loop C are formed with the notches $d d$, which receive the lips $b' b'$, formed upon the 50 edge of the cross-bar b , as shown in Fig. 1, thus fulcruming the loop C, so that in action the cross-bar f' of the loop C will grip the tug B upon the cross-bar c in rear of the tongue c' . The notches $d d$ and lips $b' b'$ also serve to 55 always maintain the proper relative positions of the main parts A C of the buckle, and also to prevent the tug from being injuriously compressed and worn by the bar f' of the loop C. Constructed in this manner the buckle is very 60 durable and very easy upon the tug, and is very convenient in adjusting the tug.

Instead of forming the cross-bar b with the lips b' , the bar might be made plain, without the said lips, if desired, and loops o may be 65 formed on or fixed to the main part A of the buckle for attaching thereto the back-band, belly-band, and breeching-straps of the harness.

Having thus described my invention, what I 70 claim as new, and desire to secure by Letters Patent, is—

1. The main part A, having the oppositely-arranged tongues $a' c'$, adapted for holding the tug B, in combination with the grip-loop C, 75 arranged to grasp the tug B, substantially in the manner and for the purposes set forth.

2. The grip-loop C, formed with the notches d , in combination with the main part A, having the cross-piece b , and devices on opposite 80 sides of its ends for holding the tug, substantially as and for the purposes set forth.

3. The grip-loop C, formed with the notches d , in combination with the bar b , formed with the lips b' , substantially as and for the pur- 85 poses set forth.

CHAS. C. BAUDER.
